CLAIM

The ornamental design for a golf ball marker, as shown and described.

DESCRIPTION

FIG. 1 is a perspective view of my new golf ball marker in accordance with a first embodiment of my invention showing my design;

FIG. 2 is a left side view thereof;

FIG. 3 is a top view thereof;

FIG. 4 is a back view thereof;

FIG. 5 is a frontal view thereof;

FIG. 6 is a bottom side view thereof; and

FIG. 7 is a left view thereof;

FIG. 8 is a perspective view of my new golf ball marker in accordance with a second embodiment of my invention showing my design;

FIG. 9 is a right-side view thereof;

FIG. 10 is a top view thereof;

FIG. 11 is a back view thereof;

FIG. 12 is a frontal view thereof;

FIG. 13 is a bottom side view thereof; and,

FIG. 14 is a right view thereof.

The broken line shown on the drawings form no part of the claimed design.

1 Claim, 6 Drawing Sheets
